(57) **CLAIM**

The ornamental design for a buoyancy water sport shirt, as shown and described.

DESCRIPTION

FIG. 1 is a front, right perspective view of a first embodiment of a buoyancy water sport shirt showing my new design;

FIG. 81 is an elevational view thereof from the left;
FIG. 82 is an elevational view thereof from the right;
FIG. 83 is a perspective view thereof from the front right in
an inside out configuration;
FIG. 84 is a perspective view thereof from the rear left in the
inside out configuration;
FIG. 85 is an elevational view thereof from the front in the
inside out configuration;
FIG. 86 is an elevational view thereof from the rear in the
inside out configuration;
FIG. 87 is a top plan view thereof in the inside out configu-
ration;
FIG. 88 is a bottom plan view thereof in the inside out
configuration;
FIG. 89 is an elevational view thereof from the left in the
inside out configuration; and,
FIG. 90 is an elevational view thereof from the right in the
inside out configuration.
The broken lines in FIGS. 1-90 show environmental struc-
ture and form no part of the claimed design.
